UNITED STATES PATENT OFFICE.

JOHN C. ROMER, OF BROOKLYN, NEW YORK.

UMBRELLA STAND.

1,413,432.

Specification of Letters Patent. Patented Apr. 18, 1922.

Application filed August 13, 1921. Serial No. 491,954.

To all whom it may concern:

Be it known that I, JOHN C. ROMER, a citizen of the United States, and a resident of the city of New York, borough of Brooklyn, in the county of Kings and State of New York, have invented a new and Improved Umbrella Stand, of which the following is a full, clear, and exact description.

This invention relates to umbrella stands and has for an object to provide an improved construction especially adapted to hold umbrellas in theatres, amusement houses and the like.

Another object is to provide an umbrella stand of simple, strong supporting members at the top and bottom, and also with suitable braces at the top and bottom whereby the stand may be readily secured to chairs or other supporting objects.

20 In the accompanying drawing—

Figure 1 is a perspective view of two chairs or seats together with an embodiment of the invention which is shown secured to the chairs.

25 Figure 2 is a perspective view on an enlarged scale of an umbrella stand disclosing one embodiment of the invention.

Referring to the accompanying drawing by numerals, 1 and 2 indicate chairs or seats 30 of the type commonly found in theatres and other amusement houses. These seats are provided with backs 3 and 4 which are somewhat rounded and which have a space 5 therebetween. This space and that afforded 35 by the rounded nature of the backs presents a floor space in which the stand 6 may be readily placed without obstructing the passage-way adjacent the seats.

The stand 6 is provided with a pair of 40 uprights 7 and 8 which diverge from the bottom to the top and are provided with outwardly turned feet 9 and 10 through which screws or other securing means may be passed for connecting the stand to the 45 floor. The uprights 7 and 8 are connected

near the bottom by a ring 11 which may be riveted or otherwise rigidly secured thereto. At the top the uprights are riveted, soldered or otherwise rigidly secured to the arc-shaped members 12 and 13, said arc-shaped members having laterally extending extensions 14 and 15 respectively. These extensions are provided with apertures for receiving securing screws or other securing means for connecting the extensions with the backs 3 and 4 of the seats 1 and 2. Preferably, the arc-shaped member 12 is integral with extension 14 and arc-shaped member 13 is integral with extension 15. These two arc-shaped members form a circle which is larger than the band or ring 11 and is adapted to easily receive an umbrella so that the same may be positioned substantially as shown in Figure 1 when the stand is in use.

It is intended that only one umbrella shall 55 be used in each stand and for this reason the stand may be made sufficiently small to fit into the unused space between or adjacent the seats 1 and 2.

What I claim is:—

1. An umbrella stand comprising a pair of uprights, each of said uprights being provided with a securable supporting foot, a ring connected to said uprights near their lower ends, and means forming a closed ring 70 structure connected to the uprights near their upper ends, said means being formed with supporting extensions adapted to be secured to a supporter.

2. An umbrella stand comprising a plurality of uprights provided with supporting securable members at their lower ends, and a pair of arc-shaped members at their upper ends, each of said arc-shaped members having a lateral securable projecting 80 extension for supporting said upper ends, said arc-shaped members being secured together and to said uprights, and providing an umbrella supporting ring.

JOHN C. ROMER.
